EX

D9532

OR D 14,545

No. 14 5x5

Jan. 15. 1884.

UNITED STATES PATENT OFFICE.

CHARLES CASPER, OF MERIDEN, CONNECTICUT.

DESIGN FOR A SALT AND PEPPER BOX.

SPECIFICATION forming part of Design No. 14,545, dated January 15, 1884.

Application filed October 23, 1883. Term of patent 3½ years.

To all whom it may concern:

Be it known that I, CHARLES CASPER, a citizen of the United States, residing at Meriden, in the county of New Haven and State of Connecticut, have invented certain new and useful Improvements in Designs for Salt and Pepper Boxes or Receptacles, of which the following is a specification, reference being had therein to the accompanying drawing, in which I have represented in side view my improved design.

I intend my design for the ornamentation of salt or pepper receptacles and like articles; and it consists, essentially, in the representation of a demijohn, substantially as shown in the drawing.

The box A is made to represent the body of

the demijohn, and the cover B is made to represent the cap or neck and the cork, the latter being provided with perforations a. The exterior of the body is ornamented in the manner shown to represent the basket-work covering common demijohns.

Having described my invention, what I claim, and desire to secure by Letters Patent, is—

The design for pepper or salt boxes, substantially as shown.

In testimony whereof I affix my signature in presence of two witnesses.

CHARLES CASPER.

Witnesses:

ROBERT H. CURTIS,
LOUIS CASPER.
